(57) **CLAIM**

The ornamental design for a machine housing with contrasting portion, as shown and described.

DESCRIPTION

FIG. 1 is a front view of a machine housing with contrasting portion according to our novel design;

FIG. 2 is a right perspective view thereof;

FIG. 3 is a left perspective view thereof;

FIG. 4 is a right side view thereof; and,

FIG. 5 is an additional left perspective view thereof, showing one possible embodiment of the design.

The broken lines are for illustrative purposes only and form no part of the claimed design.
